UNITED STATES PATENT OFFICE.

PAUL J. SITTER, OF OSHKOSH, WISCONSIN.

ADVERTISING ATTACHMENT FOR CIGAR AND CIGARETTE HOLDERS.

Application filed December 13, 1922. Serial No. 606,631.

To all whom it may concern:

Be it known that PAUL J. SITTER, a citizen of the United States, residing at Oshkosh, in the county of Winnebago and State 5 of Wisconsin, has invented certain new and useful Improvements in Advertising Attachments for Cigar and Cigarette Holders, of which the following is a specification.

This invention relates to an advertising 10 attachment for cigar and cigarette holders and has for its principal object to provide means whereby the name and address of the owner of the cigar or cigarette holder is displayed so as to enable the cigar or cigarette 15 holder to be returned to the rightful owner in case the same is accidentally lost or misplaced.

Another important object of the invention 20 is to provide an advertising attachment for cigar and cigarette holders of the above mentioned character, and which may be used for several purposes namely as an advertising medium for the particular cigar or cigarette holder and is of such a construction 25 as to enable the various display cards to be carried by the cigar or cigarette holder at various times.

A still further object of the invention is to 30 provide a cigar or cigarette holder which will detachably support an advertising display device and which will be ornamental when the same is applied to the cigar or cigarette holder and is simple in construction, inexpensive, strong, durable and 35 further well adapted for the purpose for which it is designed.

Other objects and advantages of this invention will become apparent during the course of the following description.

40 In the accompanying drawing forming a part of this specification and in which like numerals designate like parts throughout the same:—

In the drawings wherein for the purpose of illustration is shown the preferred embodiment of my invention, the numeral 1 55 designates a cigar or cigarette holder and is provided with the usual mouthpiece 2 at its smaller end as shown in the drawings. The mouthpiece 2 may be detachably secured to the cigar or cigarette holder in any suitable manner and I do not wish to confine myself to the manner in which the same is attached thereto.

The cigar or cigarette holder 1 is provided with a tapering longitudinal channel 3 in its outer face and this channel extends from the enlarged end of the cigar or cigarette holder to the smaller end thereof as more clearly shown in the drawings.

Adapted to be seated within this longitudinally extending channel 3 and fitting snugly therein when in position is a card holder 4. This card holder 4 is preferably formed of any suitable light metallic material so as to enable the same to be bent to conform to the curvature of the cigar or cigarette holder and this card holder 4 is also tapered so as to permit the same to snugly fit within the channel 3. A card holder 4 which is formed of a single piece of material has its opposite longitudinal edges bent laterally and inwardly to form parallel guide flanges 5 and 6 respectively. These flanges 5 and 6 terminate adjacent the respective ends of the card holder 4 for the purpose to be hereinafter more fully described.

A memorandum slip or identification card such as is shown at 7 in the drawings and is also provided with longitudinal tapered sides so as to permit the same to be received within the card holder 4 is adapted to be slidably received between the flanges 5 and 6 of the card holder 4 and when placed in this position is permanently held therein.

After the identification card or memorandum slip 7 has been inserted between the flanges 5 and 6 in the card holder 4 so as to display the identification card or other advertising medium the card holder together with the card held therein is placed within the longitudinally extending tapered channel 3 and suitable caps 8 and 9 respectively are adapted to be fitted on the respective ends of the cigar or cigarette holder in such a manner as to firmly hold the free ends of the card holder 4 in proper position and prevent the same from accidentally falling out of the longitudinal channel 3. The purpose of providing a longitudinal channel in 100 the outer face of the cigar or cigarette holder for receiving the card holder 4 is to prevent the card holder from sliding around the outer face of the cigar or cigarette holder 1 and furthermore will enable the flanges 5 and 6 formed on the opposite longitudinal edges of the card holder to protrude slightly above the outer surface of the cigar or cigarette holder thereby giving the same a neat appearance.

After the caps have been placed upon the 10 respective ends of the cigar or cigarette holder 1 and the advertising device is in position upon the cigar or cigarette holder the mouthpiece 2 is then inserted in the smaller end of the cigar or cigarette holder and is 15 then ready for use.

It will be readily seen that with an advertising attachment of the above mentioned character in position upon a cigar or cigarette holder it is possible and frequently the 20 case that the same becomes lost and when a person other than the owner finds the cigar or cigarette holder he will readily see by the advertising attachment thereon the name of the rightful owner and address and 25 he can thereby return the same to him. Furthermore any advertising medium or memorandum slip may be inserted upon the card holder as desired by the person having possession of the cigar or cigarette holder.

It will thus be seen from the foregoing 30 description that a cigar and cigarette holder has been provided wherein an advertising device may be readily and easily placed in position upon the same for various purposes 35 and its simplicity renders the device very efficient and also obtainable at a minimum cost.

From the foregoing description of the construction of my improved apparatus, it will 40 be seen that I have provided a simple, inexpensive and efficient means for carrying out the objects of the invention, and while I have particularly described the elements best adapted to perform the functions set forth, 45 it is obvious that various changes in form, proportion and in the minor details of construction may be resorted to; without departing from the spirit or sacrificing any of the principles of the invention.

What I claim as new and desire to secure 50 by Letters Patent is:—

1. In combination with a cigar or cigarette holder provided with a mouthpiece, of a card holder associated therewith, a card receivable in the said card holder, and means 55 carried by said first mentioned holder for retaining said card holder thereon.

2. In combination with a cigar or cigarette holder and a mouthpiece therefor, of a card holder detachably mounted on the 60 said cigar holder, said card holder provided with means for slidably receiving a card, and means carried by said first mentioned holder for retaining said card holder thereon. 65

3. In combination with a cigar or cigarette holder and a mouthpiece therefor, of a card holder extending longitudinally on the said cigar holder, caps on the ends of the said cigar holder and receiving the ends 70 of the said card holder, and a card held in the said card holder.

4. In combination with a cigar or cigarette holder, and a mouthpiece therefor, said 75 holder provided with a longitudinal channel, of a card holder fitting in the said channel, a card held in the said card holder, and a cap on each end of the said cigar holder for receiving the ends of the said card holder.

5. In combination with a cigar or cigarette holder and a mouthpiece therefor, said holder provided with a tapering longitudinal channel in its outer face, of a card holder fitting in the said tapering channel, the opposite longitudinal edges of the said card holder bent inwardly to form guide flanges, a card slidably mounted in said card holder and between said flanges, and a cap on each 85 end of the said cigar or cigarette holder 90 for receiving the ends of the said card holder.

In testimony whereof I affix my signature.
PAUL J. SITTER.
